DESIGN FOR A WHEEL HUB

William C. Roe, Elyria, Ohio, assignor to The Colson Corporation, Elyria, Ohio, a corporation of Ohio

Application May 29, 1944, Serial No. 113,799

Term of patent 14 years

(Cl. D14—30)

To all whom it may concern:

Be it known that I, William C. Roe, a citizen of the United States, residing at Elyria, in the county of Lorain and State of Ohio, have invented a new, original, and ornamental Design for Wheel Hub, of which the following is a specification, reference being had to the accompanying drawing, forming a part thereof.

Figure 1 is a front perspective view of a wheel hub showing my new design; and

Figure 2 is a side elevation thereof on a larger scale.

I claim:

The ornamental design for a wheel hub, substantially as shown.

WILLIAM C. ROE.
